ROCKING ELECTRIC TUBE FURNACE
John C. McMullen, Niagara Falls, N.Y., assignor to The
Carborundum Company, Niagara Falls, N.Y., a cor-
poration of Delaware
Filed Mar. 16, 1967, Ser. No. 623,661
15 Claims. (Cl. 13—21)

ABSTRACT OF THE DISCLOSURE

An electric tube furnace for heat treating granular materials having means for tilting a resistance tube heater downwardly towards the discharge outlet of the resistance tube and a crank drive mechanism for rocking the resistance tube about its longitudinal axis to continuously advance the granular material through the resistance tube toward the discharge outlet. Flexible electrical conductor cables are employed to deliver a high amperage current to the resistance tube.

This invention relates to electric furnaces and, more particularly, to a continuous, high temperature, rocking tube furnace.

In the field of heat treating granular material, such as abrasive grain compositions by way of example, it has been known to employ rotary continuous tube furnaces in which the tube furnace is revolved through 360°. In this manner, the granular material is continuously advanced through the furnace to prevent the grain material from adhering together and to provide a short contact time at the desired temperatures in order to prevent undue crystal growth.

Although such prior known furnaces have served the purpose for which they were designed, they have not been entirely satisfactory under all conditions of operation due to their inability to maintain controlled high temperatures and electric contact at the opposite ends of the tube to handle the large amperage required in the heat treating and sintering of certain abrasive grains.

Summary of the invention

The general purpose of this invention is to overcome the above disadvantages by providing a furnace for heat treating granular material continuously under controlled conditions of temperature, atmosphere and contact time. Means are provided for rocking the tube furnace to effect continuous movement of the granular material while simultaneously permitting effective electrical contact at each end of the tube furnace to accommodate a high current input.

Accordingly, it is an object of the present invention to provide a new and improved electric furnace.

It is another object of the present invention to provide a new and improved electric furnace for heat treating granular material continuously under controlled conditions of temperature, atmosphere and contact time.

It is a further object of the present invention to provide a new and improved electric furnace having novel means for effecting a rocking or oscillating movement of said furnace and means for tilting said furnace.

These and other objects of the invention will become more apparent upon consideration of the following de-

2

tailed description thereof when taken in conjunction with the following drawings, in which:

FIG. 1 is a side elevational view of the electric tube furnace constructed in accordance with the principles of this invention;

FIG. 2 is a front end elevational view of the structure shown in FIG. 1 with the feeding mechanism removed;

FIG. 3 is a longitudinal sectional view taken on the plane of line 3—3 of FIG. 2 illustrating the discharge end of the furnace and with parts removed to more clearly illustrate the interior of the furnace; and

FIG. 4 is a longitudinal sectional view of another embodiment of the interior of an electric tube furnace constructed in accordance with the principles of this invention.

With reference to FIG. 1 of the drawings, it will be seen that an electric tube furnace constructed in accordance with the principles of this invention comprises a shell or casing, generally designated 10, of either a square or rectangular cross section and preferably formed of asbestos board. For purposes of this description, the forward or front end of the furnace is taken to be the entrance or left end of the furnace as seen in FIG. 1. Casing 10 is provided with a forward end slab 12 and a rear end slab 14 preferably formed of graphite and each consisting of two half sections 16 and 18 (see FIG. 2) having semi-circular grooves 20 and 22, respectively, that form a circular opening for receiving and supporting an elongated hollow cylindrical resistance tube 24, preferably made of graphite, which protrudes beyond said front and rear end slabs. Resistance tube 24 is provided with an inlet end 25 at the forward end of the tube and an outlet or discharge end 27 at the rearward end of said tube. A thin strip 23 of ceramic fiber is positioned between the edges of the slabs facing each other and acts as a seal therebetween to prevent the ambient air from entering into the interior of the casing 10.

The interior space 26 of the casing 10 surrounding the resistance tube 24, is filled with a particulate mass of thermal insulating material, such as carbon black by way of example, which serves as a thermal insulator and also prevents oxidation of the exterior surface of resistance tube 24.

Casing 10 is rigidly secured onto a cradle, generally designated 28, having a pair of upper inverted U-shape brackets 30 located adjacent the ends of casing 10 and a pair of semi-circular tracks 32 rigidly secured to said brackets, respectively, by any suitable means. A plurality of structural braces 33 are suitably rigidly secured to and extend between tracks 32. Since the tracks are of identical construction and function in the same manner, it is believed that a detailed description of only one will suffice, it being understood that the same reference characters will be applied to identical elements. Track 32 is of an angled cross section and comprises legs 34 and 36. The side of the leg 36 facing tube 24 is rigidly secured to a pair of structural angle members 38 and 40 which in turn are rigidly secured to a reinforcing support member 42 mounted on the bottom of casing 10. The other side of leg 36 is adapted to ride on cam rollers 44 to facilitate the lateral rocking movement of casing 10 as will be hereinafter more fully explained. Rollers 44 are journaled for rotation on support members 46 located at either end of the furnace and carried

by a frame 48 supported on a pair of suitable standards or pedestals 50 at the rearward end of the frame and a pair of hydraulic jacks 52 at the forward end of the frame. Thus, any desired slope of the furnace can be attained by selectively raising or lowering the forward end thereof. Alternatively, frame 48 may be mounted on four rollers for easy transportation, if desired, with four jacks located adjacent to the rollers, respectively, and engageable with a ground surface to lift the rollers from the ground surface when the furnace is to be kept stationary.

Since the furnace is adapted to be tilted so that the casing 10 is inclined in a downward rearward direction, some means are necessary to prevent the casing 10 from sliding axially in such direction. Accordingly, a cam roller 54 rotatable about a substantially vertical axis abuttingly engages leg 34 of track 32 to prevent axial rearward movement of casing 10 while permitting rocking movement thereof. Cam roller 54 is journaled for rotation on bracket 56 rigidly secured to support member 46.

Means are provided for rocking or oscillating casing 10 about its longitudinal axis relative to frame 48. Such means comprises a motor 58 suitably mounted on frame 48 and having a power shaft 60 to which is rigidly secured a drive pulley 62. A drive belt 64 extends between drive pulley 62 and a driven pulley 66 to rotate shaft 68 connected to a suitable gear reduction mechanism 70 having a suitable output shaft 72.

An elongated drive arm 74 is suitably rigidly connected at one end to output shaft 72 and at the other end to a bolt 76. An elongated connecting rod 78 has a rod end bearing 80 at one end thereof pivotably connected to bolt 76 and a rod end bearing 82 at the other end pivotably connected to a bolt 84 rigidly secured to an upstanding post 86 rigidly secured to support member 42. A spacer 88 separates rod end bearing 80 from drive arm 74 and a spacer 90 separates rod end bearing 82 from upstanding post 86. Thus, it will be seen that rotation of output shaft 72 rotates drive arm 74 and by means of connecting rod 78, effects lateral oscillating movement of casing 10 about the longitudinal axis of tube 24 relative to frame 48, to advance granular material through the resistance tube. Friction is held to a minimum by the use of tracks 32 and cam rollers 44.

The graphite front and rear end slabs, 12 and 14, respectively, act as conductors and make electrical contact adjacent the forward and rearward ends of resistance tube 24 for the purpose of heating the same. A pair of water cooled terminal blocks 92 and 94 are suitably mechanically and electrically connected to graphite slabs 12 and 14, respectively. Flexible insulated conductor cables 96 and 98 carry current to terminal blocks 92 and 94 from a suitable source of electric power (not shown). A range of 3.3 to 12.3 volts is made available to the furnace through suitable step-down transformers (not shown) and due to the low resistance of the graphite resistance tube 24, the amperage input may reach as high as 3000 amperes. Because the furnace is rocked or oscillated up to approximately 132° rather than completely revolved 360° flexible cables 96 and 98 can be employed to accommodate the high amperage power rather than using troublesome sliding contacts which would be required if the furnace or tube were completely revolved.

It should be noted that the resistance tube includes a central heating section or "hot zone" portion and "cold ends" adjacent end slabs 12 and 14. The "hot zone" is substantially midway of the resistance tube and has a length of approximately 1/4 of the length of the tube in the specific embodiment described. These relative lengths are set forth for illustrative purposes only and are not intended to restrict or limit the scope of this invention.

In order to maintain the resistance tube 24 relatively cool adjacent the terminal portions, means are provided for cooling the end slabs 12, 14 and terminal blocks 92, 94. Since the cooling means employed to cool the forward

and rearward ends of the furnace are identical, it is believed that a detailed description of the cooling means for the forward end only will suffice. Such means comprise a conduit 100 leading from a suitable source (not shown) of coolant, such as water for example, by means of a flexible hose 102, said conduit 100 passing through terminal block 92. With reference to FIG. 2, it will be seen that after leaving terminal block 92, conduit 100 is directed horizontally through slab 12 in a direction normal to the longitudinal axis of resistance tube 24, then along the front of said slab and wrapped about the periphery of tube 24 as at 104, then back through the bottom portion of slab 12 in a reverse direction and back to the source through a suitable flexible hose 106.

Means are provided for delivering granular material to the graphite resistance tube 24 and comprises a charging funnel type hopper 110 which gravity feeds material onto a feeder pan 112 connected to a vibrator 114 carried by a support 116 which is connected to a structural support column (not shown). The granular material is fed onto the feeder pan 112 at a controlled rate by vibratory movement of said pan, through the spout 118, and into the inlet end of resistance tube 24. The feed rate may be adjusted by a rheostat control located on the vibrator 114 and/or by adjusting the angle of inclination of the feeder pan 112.

The contact time of grain in the "hot zone" of resistance tube 24 can be varied from about 1 minute to 8 minutes or more depending on the degree of tilt of resistance tube 24 and the rate of feed. Casing 10 and thereby resistance tube 24 can be tilted at any angle of inclination desired by actuating jacks 52. The maximum feed rate without overloading is dependent upon the degree of tilt of resistance tube 24. At any given feed rate there is a minimum angle of tube tilt that can be tolerated and any lesser degree of tilt will result in part of the feed material falling out of the inlet end.

With reference to FIG. 3, an aperture 120 is provided in resistance tube 24 in the area of the "hot zone" to accommodate the outlet end of a tube 122. During normal operation of the furnace, granular material is fed into the inlet end of resistance tube 24 and tube 122 is closed by means of a plug 124. However, under certain conditions, it is desirable to feed granular material directly into the "hot zone" in which event, plug 124 is removed and the material fed through tube 122.

As shown in FIG. 3, an opening 128 is provided in resistance tube 24 adjacent the forward end thereof, said opening communicating with a passageway 130 having an internally threaded end portion for accommodating connections for conduits which deliver selected inert gases to the tube from a suitable source. Normally, when the furnace is used as shown in FIG. 3, passageway 130 is closed off by a suitable plug 131.

As shown in FIG. 3, a gas tight metallic cover 133 is mounted over the outlet end of resistance tube 24. A graphite ring 135 is provided within cover 133 in abutting relationship with the end of resistance tube 24 and acts as a bearing against which the end of tube 24 may rock relative thereto. A gas inlet 137, such as an elbow type fitting for example, is rigidly secured into the end wall of cover 133 and is provided with a threaded end portion for accommodating connections for conduits which deliver selected inert gases to the tube from a suitable source (not shown). A funnel spout 138 is provided in the bottom of cover 133 for permitting discharge of the granular material into a suitable gas tight receptacle 139. An inert gas is introduced under pressure through fitting 137 and is exhausted through the inlet end of resistance tube 24. A porous graphite ring 140 is provided at the inlet end of resistance tube 24 and disposed about spout 118 to preclude the ambient air from entering into said tube while permitting the inert atmosphere in the resistance tube 24 to bleed out therethrough. Spout 118 fits loosely within

graphite ring 140 to permit relative rocking motion there-

between. Alternatively, a suitable burner ring may be employed at the inlet end of resistance tube 24 to prevent oxygen from entering into said inlet end.

In operation, the furnace is tilted at the proper angle of inclination in accordance with the contact time of grain desired in the "hot zone." The rate of feed of material into the resistance tube is adjusted by either tilting feeder pan 114 and/or controlling the vibratory motion of said pan by means of a rheostat control. Electric current is supplied to the resistance tube from a suitable source by means of cables 96, 98, terminal blocks 92, 94, and graphite slabs 12, 14. Motor 58 is started to effect rotation of the crank drive mechanism and thereby cause the casing 10 and resistance tube 24 to be rocked or oscillated about the longitudinal axis thereof. FIG. 2 illustrates in phantom the position of the casing 10 when the connecting rod 78 has substantially reached the end of its "throw." Preferably, the furnace is given an oscillation of 132° but this may be adjusted, as desired, by simply changing the effective length of the connecting rod 78 by means of its threaded end portions.

The combined effect of the tilting orientation and the rocking motion applied to the tube furnace advances material continuously at a controlled rate through the furnace from the inlet end, through the "hot zone" and ultimately to the outlet end. When conditions warrant, material may be fed directly to the "hot zone" by means of tube 124. During the passage of material through the resistance tube, a non-reactive atmosphere is maintained in the resistance tube by introducing a suitable inert gas through the gas inlet 137.

As a result of this invention, an improved electric furnace is provided for treating granular material continuously under controlled conditions of contact time in the "hot zone," temperature and atmosphere in an improved and more efficient manner. By the provision of tilting means and means for rocking or oscillating the casing and thereby the resistance tube, granular material is continuously advanced through the tube furnace while permitting the high amperage power input necessary to effect the heat treating operation. This high amperage current is delivered to the resistance tube through flexible cables. Another advantage residing in the use of the furnace of this invention is that material can be fed directly into the "hot zone," an expedient which could not be accomplished with a rotary furnace.

FIG. 4 illustrates another embodiment of the electric furnace of this invention which is very similar to the above-described embodiment with the exception of providing an insert tube within the graphite resistance tube and eliminating the metallic cover of the outlet end of the tube. All of the other structural features and their resultant functions are duplicated as disclosed in the embodiment of FIGS. 1-3 and the same reference characters primed are used to identify elements which are similar to those employed in the first embodiment.

With reference to FIG. 4, it will be seen that an elongated, thin walled, impervious, refractory insert tube 134, preferably made of alumina, is encased within resistance tube 24'. An opening 136 is provided in the wall of the tube 134 for accommodating tube 122'. A long staple inorganic, permeable, ceramic fibrous material 142 is positioned between insert tube 134 and resistance tube 24' adjacent the opposite ends of said insert tube to preclude the ambient air from entering therebetween and since the inert atmosphere introduced through passageway 130' and opening 128' to prevent oxidation of resistance tube 24' is at a greater pressure, it may be slowly exhausted through the permeable material 142. Moreover, the ceramic fibrous material 142 also acts as a support in positioning insert tube 134 within resistance tube 24'.

The advantage residing in the second embodiment is that the insert tube can be utilized under oxidizing and neutral conditions. Under reducing conditions the insert tube can be removed and the graphite tube alone can

be used. It will thus be seen that the furnace may be employed in any atmosphere from oxidizing to reducing.

Although the above embodiments were described in connection with a resistance tube type heater, it should be appreciated that the principles of this invention contemplate the use of an inductively heated tube in which an induction coil may be wrapped about the graphite tube and energized to heat the same.

Preferred embodiments of the principles of this invention having been hereinabove described and illustrated, it is to be realized that variations and designs may be applied without departing from the broad spirit and scope of this invention as defined in the appended claims.

I claim:

15. 1. An electric furnace comprising: a frame; a cradle movably supported on said frame; a casing carried by said cradle and movable therewith; a generally horizontally disposed refractory tube having a longitudinal axis and mounted in said casing for movement therewith, said tube having a material inlet end and an outlet end; means for electrically heating said tube; means on said frame for adjustably tilting said casing and said tube downwardly along the longitudinal axis thereof toward the outlet end of said tube; and means for oscillating said cradle, casing, and tube about the longitudinal axis of said tube.
20. 2. An electric furnace as defined in claim 1 in which said tube is composed of graphite.
25. 3. An electric furnace as defined in claim 2 in which electrical contacts are provided for said tube whereby to supply electrical current to said tube and heat it by its resistance.
30. 4. An electric furnace as defined in claim 3 including a substantially gas-tight cover encasing and adapted for relative rotary movement with respect to the outlet end of said tube.
35. 5. An electric furnace as defined in claim 4 including a gas inlet in said gas-tight cover for providing an inert atmosphere in said tube.
40. 6. An electric furnace as defined in claim 5 including means adjacent the inlet end of said tube for precluding the admission of air into said tube while permitting the bleeding off of said inert atmosphere therethrough.
45. 7. An electric furnace as defined in claim 2 in which said tube is provided with a refractory ceramic lining.
50. 8. An electric furnace as defined in claim 7 in which said lining is in the form of a refractory ceramic tube and refractory ceramic fibrous material is positioned around said refractory tube and within said graphite tube adjacent the ends of the latter.
55. 9. An electric furnace as defined in claim 8 in which an inert gas inlet is provided in said graphite tube to provide an inert atmosphere between said graphite tube and said refractory ceramic tube.
60. 10. An electric furnace as defined in claim 8 in which said refractory ceramic tube has a second material inlet intermediate said first material inlet end and said outlet end.
65. 11. An electric furnace as defined in claim 1 in which a particulate mass of thermal insulating material is deposited between said tube and the interior surface of said casing.
70. 12. An electric furnace as defined in claim 1 in which said tube has a second material inlet intermediate said material inlet end and said outlet end.
75. 13. An electric furnace comprising a frame; a cradle movably supported on said frame; a casing movable with and carried by said cradle; a graphite tube mounted in said casing for movement therewith and having its longitudinal axis generally horizontal, said tube having a material inlet end, an outlet end, and a second material inlet intermediate said ends; a particulate mass of thermal insulation within said casing around said tube; means for supplying electrical current to said tube whereby to heat said tube by its own resistance; means for supplying an inert gas to the interior of said tube; means for adjust-

ably tilting said tube whereby to change its inclination to the horizontal; and means for oscillating said cradle, casing, and tube about the longitudinal axis of said tube.

14. An electric furnace as defined in claim 13 in which said graphite tube is provided with a refractory ceramic

5 said lining is in the form of a refractory ceramic tube and refractory ceramic fibrous material is positioned around said refractory tube and within said graphite tube adjacent the ends of the latter.
